2,468,415

METHOD OF AND APPARATUS FOR
BURNING COAL

Daniel E. Stair, Chicago, Ill.

Application August 17, 1945, Serial No. 610,991

10 Claims. (Cl. 110—32)

1

This invention relates to an improved method of burning coal and to certain new and useful improvements in apparatus for carrying out the several steps of the improved method.

A principal object of the invention is to provide an improved and practical method of burning coal, whereby coal of various qualities may be converted and burned either individually or as mixed fuel in the same apparatus.

Another principal object is to provide a method for burning coal which involves complete conversion of the volatiles and the fixed carbons into heat energy before delivering the hot combustion products into the heat transfer chamber of the heating apparatus, whereby the maximum heat units are utilized in connection with the heating operation.

The various methods of burning coal in fuel beds, as heretofore practiced, have included introducing the coal directly into the heat transfer chamber, to-wit, the usual fire box of a furnace, which is in close association with the boiler. Consequently, the temperature of the fire bed is so reduced by the transfer of heat to the boiler or to the water coils thereof, that insufficient heat is retained in the fire bed to break down the cellular structure of bone coal surrounding particles of fixed carbon and thereby liberate this carbon in the form of heat units.

It is a specific object of the present invention to provide an improved method for burning coal in a fire bed in which the coal is advanced in an angular course through zones of progressively increasing temperatures, which temperatures insure complete liberation of all combustible substances contained in the coal, and whereby the angular configuration of the fire bed will permit different amounts of air to pass through different zones of the fire bed and thereby insure complete and efficient combustion of the free and the fixed carbons of the coal. For example, the configuration of the coal bed is such that there is less resistance to the air currents passing through the cooler upper portion of the bed in which a major portion of the more volatile combustibles are liberated or to which they migrate from other zones. In this way, the volatile gases are supplied with the proper amounts of combustion air and the air flow through the lower and higher temperature zones of the bed may be restricted so as to avoid cooling the incandescent fuel.

A further object of the invention is to provide a combustion chamber in which the zone of highest temperature will be near the bottom of the chamber and thereby expedite the removal

2

of the ash and other noncombustible portions of the fuel from the fuel bed in the form of liquid slag. In this way, the invention avoids the collection of fly ash in the flues of the boiler and also avoids the matting together of the incandescent fuel particles in the combustion chamber or the formation of clinkers therein in a manner to obstruct the passage of air.

Another object is to provide an improved 10 method of burning coal in which the temperature changes in the heat transfer chamber of the heating apparatus will be gradual and consequently avoid the recurrent abrupt expansion and contraction of the boiler and other metal parts 15 of the furnace.

Another object is to provide an improved apparatus having a preferred form of combustion chamber adapted for use in connection with the various furnace constructions now in general use 20 and which is particularly adapted for use in connection with the simplified means herein shown for automatically advancing the coal through the combustion chamber.

A further object of the invention is to provide 25 a fuel advancing mechanism in the form of a revolvable retort which will move the coal through the combustion chamber and at the same time agitate the coal within the retort, by moving it from the lower portion to the upper portion 30 thereof and thereby keep it relatively loose so that the combustion supporting air may pass freely through the upper portions of the coal bed to combine with the free carbons liberated from the coal.

Another object of the invention is to provide 35 improved structure for forming adequate air passages leading into the lower portion of the coal bed within the combustion chamber and to provide controllable means for varying the 40 amount of air entering the combustion chamber in proportion to the heating requirements of the furnace. In this connection, the invention includes the provision of a suction fan and dampers interposed between the fan and the combustion 45 chamber, the dampers being controlled to vary their positions relative to the temperature or pressure of the boiler so that the air drawn into the combustion chamber will be proportional to the furnace temperatures or the boiler pressure.

Another object of the invention is to provide 50 a convenient means for removing the revolvable retort when it is necessary to repair any part of the combustion chamber, whereby these repairs can be taken care of with minimum delay and inconvenience.

Another object is to provide a simplified means for removing and disposing of the slag discharged from the combustion chamber. In this connection, the invention includes the provision of a pit and a container removably positioned therein to receive waste water; the molten slag being discharged from the combustion chamber directly into the water filled container.

The improved method of the present invention and a preferred form of apparatus for carrying out the steps of the method are illustrated in the accompanying drawings wherein:

Fig. 1 is a front view of a revolvable retort, and the mechanisms associated therewith.

Fig. 2 is a side view of the structure shown in Fig. 1 showing parts of the furnace broken away to illustrate the path of travel of the combustion gases.

Fig. 3 is a vertical section taken substantially on line 3—3 of Fig. 1 but illustrating only a portion of the boiler and heat transfer chamber of the furnace.

Fig. 4 is a fragmentary sectional view taken substantially on line 4—4 of Fig. 3, looking in the direction indicated by the arrows.

Fig. 5 is a similar fragmentary sectional view which is taken substantially on line 5—5 of Fig. 3.

Fig. 6 is an enlarged fragmentary sectional view illustrating an I-beam grate construction which provides a series of tuyère passages leading into the lower portion of the combustion chamber.

Fig. 7 is a face view of a base ring which encloses a gear for rotating the revolvable retort.

Fig. 8 is a fragmentary plan view of certain of the operating elements which are shown removed from their operative positions on the base ring for the purpose of clearness.

Fig. 9 is a fragmentary sectional view taken through the base structure substantially on line 9—9 of Fig. 1.

Fig. 10 is a detail view of side frame members for slidably supporting the retort structure in its operative position.

Fig. 11 is a partial sectional view to further illustrate the supporting frame structure of Fig. 10, the said sectional view being taken on line 11—11 of Fig. 2.

According to the improved method which forms a part of the present invention, the coal bed is so maintained as to provide a general triangular configuration in vertical section so as to progressively decrease the mass of material toward the upper limit of the bed and thereby permit combustion air to pass more freely through the upper portions of the bed than through the lower portions thereof. In order to maintain a coal bed of the desired configuration, a combustion chamber 10 is provided which includes a relatively large bowl portion 11 for receiving the fuel and an outlet passage 12 connected therewith. The said bowl portion 11 and the outlet passage extend at angles to each other so that the longitudinal axis of the bowl portion extends upwardly and outwardly from the furnace and the longitudinal axis of the discharge passage extends upwardly and inwardly. This passage communicates with the heat transfer chamber 13 of the furnace. The coal is passed through a retort so as to subject it to heat and thereby release large amounts of the free carbon in the form of combustible gas before the solid fuel is delivered into the combustion chamber. The said retort is in the form of a hopper for receiving the coal. It is provided on its inner surface with inwardly projecting vanes and is rotated about the said upwardly and

outwardly inclined axis so as to keep the coal in agitation by continuously moving it from the lower portion of the retort into the upper portion thereof. This agitation of the coal keeps it loose so as to permit the air to flow through the upper strata of the fuel bed with less obstruction than through the lower portion, but higher temperature zones of the bed. According to the improved method, the fuel bed is maintained at a sufficient depth and the air is passed lengthwise through the bed, with increasing resistance toward the lower portions thereof so that the temperature of the fuel bed progressively increases from the top to the bottom thereof, the zone of highest temperature being at the lower portion of the combustion chamber. In this way, the several stages of combustion will be carried out simultaneously. For example, the high volatile free carbons contained in the coal are distilled off in the cooler upper strata of the fuel bed, particularly that portion of the bed which is contained in the retort and in the cooler portion of the combustion chamber adjacent to the retort. Certain other of the free carbons are liberated from the coal in the lower zone of higher temperature and migrate upwardly through the fuel bed toward the upper strata thereof wherein they are mixed with the combustion air passing through this strata of the coal bed. The fixed carbons of the coal which require higher temperatures to convert them into combustible gases are liberated from the fuel in the lower and consequently higher temperature zones of the fuel bed. The final stage of combustion takes place in the lowest strata of the fuel bed which is maintained at a sufficiently high temperature to break down the bone coal cellular structure so as to free the combustible carbons entrapped therein and to liquefy the ash and other noncombustible substances contained in the coal so that these materials are removed from the fire bed in the form of a molten slag.

The air is preferably drawn through the fuel bed by a controlled suction device as distinguished from an ordinary stack and the operation of this device together with dampers associated therewith are controlled by temperature responsive means associated with the furnace. In this way, the volume of air drawn through the fire bed will be controlled in relation to the temperature desired to be maintained. The combustible gases distilled from the coal and migrating toward the upper portion of the fuel bed are carried by the air currents into the higher temperature zones where they are burned. For example, a portion 55 of the gasified fuel may be carried downwardly and directed into the heat transfer chamber through the discharge passage 12 as shown by the path of arrows in Fig. 3. Another portion of the said gases may be directed into the heat transfer chamber through a plurality of ducts 14 which pass through the wall of the furnace immediately above the arch 15 of the discharge passage 12. Inasmuch as the lower portion of the fuel bed provides greater resistance to the passage of air, my improved method includes the introduction of air through tuyère passages which extend into the fuel bed at a location intermediate the top and bottom thereof and through passages at other locations near the bottom of the fuel bed. These 65 passages are provided with damper doors which function in connection with flue dampers to control the volume of air passing into the combustion chamber. Preferably, the same device which is utilized to control the position of the flue dampers 70 controls the position of the said damper doors.

In addition to agitating the coal contained in the retort, the coal is advanced through the combustion chamber in a downwardly and then upwardly directed path so that each particle of coal will pass through the several temperature zones of the combustion chamber and thereby be completely converted into combustible gases and the hot products of this combustion are directed into the heat transfer chamber of the heating apparatus. Inasmuch as the complete conversion of the coal takes place outside of the heat transfer chamber, the absorption of heat by the boiler or by water coils arranged in the furnace does not materially affect the temperature of the fuel bed and therefore makes it practicable to maintain the high temperatures required to liberate all combustible products of the fuel.

The apparatus, as illustrated in this application, for carrying out the several steps of the improved method includes means defining the bowl 11 of the combustion chamber 10 and the discharge passage 12. The passage 12 connects the lower portion of said bowl with the heat transfer chamber 13 of the furnace structure. Preferably, the said bowl 11 is formed with a circular coal receiving opening and with side walls which, except for the portion designated A in Fig. 3, unite with a curved bottom portion as shown in Fig. 5 of the drawings. The side wall A of the bowl 11 terminates at the entrance end of the discharge passage 12 and diverges from the plane of the mouth of the bowl 11 so that the combustion chamber will have a general triangular configuration in vertical section as shown in Fig. 3 of the drawings, and the wall A will define the general slope of the inner inclined face of the fuel bed.

The combustion chamber is separated from the heat transfer chamber 13 of the furnace by means of a wall of refractory material which defines the discharge passage 12. This manner of construction removes the fuel bed from the cooling influence of the boilers 16 and other heat absorbing elements located in the transfer chamber and also makes it practicable to make the walls defining the said chamber 11 and passage 12 as thick as maybe necessary to provide the desired heat insulation to maintain relatively high temperatures within the combustion chamber. In connection with the combustion chamber as herein illustrated, the present disclosure includes a tubular boiler 16 arranged horizontally above the heat transfer chamber 13 so that the hot combustion products will flow through the boiler flues. It will be understood however that the specific form of boiler and heat transfer chamber is not important, but is shown herein merely for convenience of illustration. The combustion chamber and other parts associated therewith for advancing the fuel through the combustion chamber may be used in connection with furnace structures and boilers of various types.

The lower portion of the combustion chamber 10 is provided with air inlet openings 17, 17 for the admission of air; the amount of air being controlled by means of dampers 18, 18 in connection with other damper means hereinafter described. A series of I-beams 19 are arranged in close relation to each other to provide a grate structure 70 extending around a portion of the combustion chamber. The top webs 20 of the I-beams are, preferably, of less width than the bottom webs 21 so as to permit the said I-beams to be arranged in a radial pattern as shown in Figs. 4 75

and 6 of the drawings. The spaces between the said I-beams provide tuyère passages 22 through which air is directed into the lower portion of the combustion chamber 10 so that an adequate supply of air will pass through the body of material lying in the lower and higher temperature zones of the combustion chamber 10. The coal is constantly fed into the retort so as to keep a desired level of coal therein. By reason of the configuration of the combustion chamber and the inclined arrangement of the revolvable retort, the normal upper and lower capacity lines of the fuel bed are inclined relative to each other as indicated by the reference numerals 23 and 24 respectively in Fig. 3 of the drawings. The side of the fuel bed represented by the numeral 24 extends across the discharge passage 12 while the other inclined side of the fuel bed extends diagonally across the retort chamber.

The retort is of circular structure and is composed preferably of a plurality of segments 25. The segments are made of cast metal and have inwardly extending flanges 26 at their opposite edges which are secured to corresponding flanges of an adjacent segment to provide inwardly extending vanes 27. The outer ends of the retort segments 25 are secured together by means of a flanged ring 28, one flange of which overlaps the outer ends of the segments and another flange 29 thereof extends inwardly for a short distance along the inner edges of the vanes 27. Preferably, the seams between adjacent segments 25 of the retort and between the outer ends of the segments and the flange ring 28 are sealed to provide air tight constructions. The upper portions of the retort, therefore, serve as a trap for retaining any of the distilled free carbons which may rise upwardly through the coal bed and enter the upper portion of the retort. The combustible gases thus entrapped will be entrained with the air currents passing into and through the retort and carried into the high temperature zone for combustion. The lower portion of the retort is tapered to provide a cone configuration and the outer surface of this portion is provided with a ring gear 30. The gear 30 may be secured to the retort by any suitable means, for example, by bolts 31 which extend through the ring gear and into a shoulder portion 32 formed on the retort segments. The teeth 31 of the ring gear are formed on the outer periphery thereof and are of a width less than the thickness of the ring. The lower face 32 of the ring gear and the smooth peripheral portion 33 thereof, adjacent the teeth 31 provide bearing spaces which engage corresponding surfaces of a base ring 34 which seats upon the upper face of a base casting 35.

The base casting 35 is of rectangular construction, but is provided with a circular opening 60 which receives an inwardly extending rib 36 formed on the bottom surface of the base ring adjacent its inner perimeter. The central opening through said base casting 35 together with the inclined outer wall of the retort define an air space 37 which extends entirely around the retort and communicates with the bowl portion 11 of the combustion chamber. At the lower portion of the said bowl 11, the said air is delivered into the combustion chamber through the space intervening between the grates and the outer surface of the retort and through the tuyère passages 22 between the grate members. The lower portion of the base casting 35 is provided with an air inlet opening 38. The opening and closing of this inlet opening is controlled by a

damper door 39 which is automatically opened and closed simultaneously with the opening and closing of damper doors 18, 18.

The retort is rotated preferably at a low rate of speed by means of an electric motor 40 which may be supported on a shelf 41 secured to the base ring 34. The motor shaft is provided with a worm (not shown) which meshes with a worm gear 42 enclosed within a housing 43 (Figs. 1 and 8). The worm gear 42 is connected by means of a shaft 44 with a pinion 45 which meshes with the teeth 31 of the ring gear 30.

It will be seen from the above description that the operation of motor 40 will rotate the retort about its axis which inclines at a suitable angle to maintain the capacity line 23 of the fuel within the retort substantially at the inclination shown in Fig. 3 of the drawings. The lower ends of the retort segments are provided with impeller elements 46 which are in the form of Z-bars curved to conform to the circular structure of the retort segments and having their lower outer-turned flanges 47 inclined in the direction of their length and in the direction of rotation of the retort so as to exert wedging pressure on the body of fuel within the bowl portion 11 of the combustion chamber. During this rotation of the hopper, the inwardly projecting vanes 27 thereof keep the coal in constant agitation by moving the coal from the lower portion of the retort and discharging it onto the upper portion of the coal bed. The supply of coal to the retort may be maintained by any suitable means, for example, a spout 48 which may lead from a source of coal supply (not shown).

Draft Control

The amount of combustion air drawn into the combustion chamber is controlled, preferably, by induction means, for example a suction fan 49, which is preferably operated at a continuous speed by means of a suitable motor 50. The fan is interposed in the draft passage 51 leading from the discharge end of the boiler 16 to the chimney 52. The degree of suction for drawing air into the combustion chamber and for inducing the flow of the products of combustion through the boiler tubes is controlled by the position of a damper 53 positioned in the draft passage 51. The position of the damper 53 and likewise the positions of the damper doors 18, 18 and 39 are controlled by means of a pressure motor 54 which responds to temperature changes within the furnace. The pressure actuated motor 54 is of conventional construction and includes an arm 55, the inner end of which is pivoted at 56 to the motor casing 54 and is operated by a pressure actuated rod 57. The outer end of the lever 55 is connected to the damper 53 by means of a cable 58 which extends over pulleys 59 and 60, the latter of which is connected to the damper 53. The free end of the cable 58 is provided with counter weights 61 so as to maintain the cable taut at all times. The damper doors 18, 18 and 39 are connected to the arm 55 of the pressure motor 54 by means of cooperating connecting rods 62, 63 and 64, the latter of which connects with the bell crank 65. Similar connecting rods for operating the damper doors are arranged at opposite sides of the furnace and may be operatively connected together by any suitable means, for example, shaft 66 which connects the pulleys 59 located on opposite sides of the furnace. When it is desired to manually increase the flow of com-

bustion air into the combustion chamber, for example when increasing the fire after a prolonged inactive period, a damper 67 positioned in a branch draft passage 68 leading to the chimney 52 may be adjusted to any desired position. However, during normal operation of the furnace, the damper 67 is closed. After the temperature of the furnace approaches its maximum, the operation of the pressure motor 54 will function to proportionately adjust the positions of the damper 53 and the positions of the damper doors 18 and 39 so as to supply the necessary amount of combustion air to maintain a desired temperature. As the load or heat absorption increases, the pressure motor 54 will function to gradually open the dampers to admit a larger volume of combustion air through the fuel bed and thereby increase the volume of combustion.

These changes, however, will be relatively gradual so as to avoid abrupt changes in temperature of the boiler and consequently avoid the recurrent expansion and contraction of the boiler and other metal parts of the furnace.

When it is desired to bank the fire, the cable 58 and rods 62 may be disconnected from the motor arm 55 so that the damper 53 and the damper doors 18 and 39 may be closed. The manually controlled damper 67 may then be opened slightly so as to permit a small amount of combustion air to be drawn through the fuel bed by the natural or chimney draft.

Slag disposal

As previously indicated in connection with the disclosure of the improved method, the ash and other noncombustible substances contained in the fuel are removed in the form of liquid slag. This slag is discharged from the bottom of the combustion chamber through a duct 69 into a cinder disposal pit 70 located below the floor level of the furnace room. A removable container 71 in the form of a bucket is positioned in the pit 70 below the slag discharge duct 69, preferably a pipe 72 discharges waste water into the container 71 so that the slag, when discharged from the combustion chamber, will fall directly into a body of water and thereby instantaneously be cooled. This cooling action on the slag, as it is discharged from the combustion chamber, forms it into small particles. When the container 71 is filled with waste water, it will overflow into the pit 70 until the water reaches the level to be discharged through an overflow passage 73. When it is desired to empty the container 71, a drain plug 74 is removed so as to drain the water from the pit 70. The bail 74a of the container is then connected to a suitable hoist 75 to lift the container out of the pit as indicated in dot and dash lines in Fig. 3. The hoist 75 is movably supported on the over-head frame structure by means of a carriage 76. The carriage operates on the outer flanges of I-beams 77, 78 of which the over-head frame is formed.

Removal of fuel hopper

In order to facilitate repairing the grates or the masonry of the combustion chamber, the retort is slidably supported on a carriage 79 which is movably supported on the inner flanges of said I-beams 77, 78. The carriage 79 is provided with depending frame members 80 and 81, the latter of which is inclined at an angle corresponding to the inclination of the axis of the hopper and slidably supports channels 82, 83 which are secured to diametrically opposite sides of the base ring

34. Cables 84 and 85 connect the channels 82, 83 with a windlass 86 mounted in the framework of the carriage 79. By rotating the windlass 86, the fuel hopper together with the base ring 34 may be drawn upwardly and outwardly until the impellers 46 at the lower end of the hopper clear the base casting 35. The carriage 79 may then be moved lengthwise of the I-beams 77, 78 to any suitable position which will provide free access to the combustion chamber for purpose of repair.

I claim:

1. The method of burning coal which consists in forming a fire bed of substantially triangular configuration in vertical longitudinal section so that the volume of coal therein progressively increases toward the bottom of the bed, drawing a stream of air through the upper portion of the bed from one inclined face to the other, igniting and burning the fuel in the lower portion of the bed and along said opposite inclined face, feeding coal to the inclined face of the bed at the air receiving side thereof and forcing it toward the burning inclined face of the bed, drawing air into the lower portion of the bed intermediate the inclined faces thereof, and agitating the coal adjacent said feeding side of the bed by moving the coal from a lower to an upper portion of the bed.

2. A coal burning apparatus comprising means defining a heat distributing chamber, means defining a combustion chamber of angular configuration in vertical longitudinal section separate from the heat distributing chamber but communicating therewith, means including a revolvable retort for delivering coal into the combustion chamber to maintain it filled so as to form a fuel bed therein conforming to the shape of the combustion chamber and for agitating the coal adjacent the receiving end of the combustion chamber, impeller means carried on the retort for forcing the fuel through the combustion chamber, and means for passing air lengthwise through the fuel bed to mix with the combustion gases liberated from the burning coal.

3. A coal burning apparatus including means defining a combustion chamber having a receiving opening for coal, a retort revolvably supported in the said coal receiving opening of the combustion chamber and revolvable about an axis which inclines upwardly and outwardly from the combustion chamber and adapted to receive coal and deliver it into the combustion chamber, and impeller means carried by the retort for advancing the coal through the combustion chamber.

4. A coal burning apparatus including means defining a combustion chamber having a receiving opening for coal, a retort supported to extend into the said coal receiving opening of the combustion chamber and revolvable about an axis which inclines upwardly and outwardly from the combustion chamber and adapted to receive coal and deliver it into the combustion chamber, and impeller means comprising a series of wedge shaped members carried by the retort for advancing the coal through the combustion chamber.

5. A coal burning apparatus including means defining a combustion chamber having a receiving opening for coal, a retort supported to extend into the coal receiving opening of the combustion chamber and revolvable about an axis which inclines upwardly and outwardly from the combustion chamber and adapted to receive coal and deliver it into the combustion chamber, impeller means comprising a series of wedge shaped mem-

bers carried by the retort and extending into the coal receiving opening of the combustion chamber for advancing the coal through the combustion chamber, and mechanical means for rotating said coal supply retort.

6. In a coal burning apparatus including means defining a combustion chamber having a receiving opening for coal, a retort having an open coal receiving end and supported to rotate about an upwardly and outwardly inclined axis with its inner end extending into the coal receiving opening of the combustion chamber to receive heat therefrom and deliver the coal into said combustion chamber, means for rotating the retort, and inwardly extending vanes fixed to the retort and movable therewith for agitating the coal contained therein during the rotation of the retort, and a flange projecting inwardly from the side wall of the retort to partially close the open end thereof and form a gas retaining trap.

7. In a coal burning apparatus including means defining a combustion chamber having a receiving opening for coal, a retort for receiving coal and for delivering it into the combustion chamber and comprising a plurality of segments secured together and supported to extend into the coal receiving opening of the combustion chamber and revolvable about an inclined axis, means for rotating the retort, means at the junction of said segments defining inwardly extending vanes movable with the retort for agitating the coal during the rotation of the retort, and a circular flange projecting inwardly from the side wall of the retort to partially close the open end thereof and form a gas retaining trap.

8. A coal burning apparatus including means providing a heat transfer chamber, means defining a separate combustion chamber formed with a coal receiving bowl having an upwardly and outwardly inclined axis and an upwardly and inwardly inclined passage leading from said bowl into said heat transfer chamber, there being a plurality of ducts connecting the upper portion of said combustion chamber with said heat transfer chamber, a retort for heating the coal before it enters the combustion chamber, a base ring for supporting said retort with the lower end of the retort extending into the coal receiving opening of the combustion chamber, the said base ring also defining an air passage for supplying air to the combustion chamber throughout the entire circumference of the coal receiving opening of the combustion chamber.

9. A coal burning apparatus including means providing a heat transfer chamber, a separate combustion chamber in the form of a bowl having an upwardly and outwardly inclined axis and an upwardly and inwardly inclined passage leading from the bowl into said heat transfer chamber, there being a plurality of ducts connecting the upper portion of said combustion chamber with said heat transfer chamber, a retort supported to extend into said bowl of the combustion chamber and adapted to receive coal and deliver it into the combustion chamber, means defining an air passage communicating with the entire circumference of the coal inlet opening of the combustion chamber for supplying air to the combustion chamber at the lower end portion of the retort, suction means for drawing air from said air passage through the coal, and means including a damper positioned in the flow path of said air and adapted to be moved toward and away from its closed position to vary the flow of air through the coal.

11

10. A coal burning apparatus including means defining a heat transfer chamber, means defining a separate combustion chamber in the form of a bowl having an upwardly and outwardly inclined axis and defining also an upwardly and inwardly inclined passage leading from said bowl into said heat transfer chamber, a retort supported to extend, at its lower end, into said combustion chamber and adapted to receive coal and deliver it into the combustion chamber, means defining an air passage extending entirely around the lower end of said retort for supplying air to the combustion space throughout the entire circumference of the coal receiving opening of the combustion chamber, and grate elements arranged in close relation to each other along a lower surface of said bowl to provide tuyère passages leading from said air passage into the lower portion of the combustion chamber.
